HENRY SANTROCK, OF KENSINGTON, KANSAS.

HOISTING APPARATUS FOR SILOS, &c.

1,152,053.

Specification of Letters Patent. Patented Aug. 31, 1915.

Application filed November 14, 1914. Serial No. 872,151.

To all whom it may concern:

Be it known that I, HENRY SANTROCK, a citizen of the United States, residing at Kensington, in the county of Smith and State of Kansas, have invented a new and useful Hoisting Apparatus for Silos, &c., of which the following is a specification.

The invention relates to improvements in hoisting apparatus for silos, etc.

10 The object of the present invention is to improve the construction of hoisting apparatus and to provide a simple, practical, and efficient hoisting apparatus of comparatively inexpensive construction, designed for use in silo pits and elsewhere, and capable of being readily transferred from one silo pit to another, so that a single hoisting apparatus may be operated in connection with a number of silos.

20 A further object of the invention is to provide a hoisting apparatus of this character adapted to be operated by a person within a pit and capable of automatically dumping its contents and of enabling such person to haul up as much silage as may be required without leaving the pit before the desired amount has been obtained.

With these and other objects in view the invention consists in the construction and 30 novel combination of parts hereinafter fully described, illustrated in the accompanying drawings, and pointed out in the claims appended hereto, it being understood that various changes in the form, proportion, size 35 and minor details of construction, within the scope of the claims, may be resorted to without departing from the spirit or sacrificing any of the advantages of the invention.

40 In the drawings:—Figure 1 is a side elevation of a hoisting apparatus constructed in accordance with this invention and shown applied to a silo pit, the bucket being lowered. Fig. 2 is a side elevation of the upper 45 portion of the same, parts being in section, and the bucket being in its dumping position. Fig. 3 is a transverse sectional view taken substantially on the line 3—3 of Fig. 2. Fig. 4 is a detail horizontal sectional view on the line 4—4 of Fig. 1. Fig. 5 is a detail perspective view of the bucket. Fig. 6 is a horizontal sectional view on the line 6—6 of Fig. 1, illustrating the construction of the side catches of the bucket. Fig. 7 is 55 a detail sectional view illustrating the manner of mounting the pivoted eyes on the pro-

jecting arms of the bucket. Fig. 8 is a detail sectional view on the line 8—8 of Fig. 7.

Like numerals of reference designate corresponding parts in all the figures of the drawings.

In the accompanying drawings, in which is illustrated the preferred embodiment of the invention, 1 designates a portable main or supporting frame designed to be supported over the top of a silo pit 2 by means of suitable beams or planking and adapted to be readily transferred from one silo pit to another. Although the hoisting apparatus is shown in the accompanying drawings in connection with a silo pit, it may be used in various places for hoisting any kind of material. The main or supporting frame, which may be of any desired construction, is provided at the top with front and rear 75 bearings 3, in which is journaled a horizontal shaft 4 carrying a hoisting drum 5 and having keyed or otherwise secured to it a relatively large pulley 6 located at the rear end of the drum 5 and provided with a 80 grooved periphery for the reception of an endless operating rope or cable 7, which is maintained taut by a weight 8. No claim is made in the present application to the relatively large peripherally grooved pulley 85 6 and the weighted endless operating rope, as this forms the subject matter of my co-pending application Serial No. 818,996, filed Feb. 16, 1914.

The drum 5 has secured to it one end of 90 a hoisting rope 9, which is secured at its other end to a bail 10 of a bucket 11. The hoisting rope or cable is caused to wind uniformly around the drum by means of a rope guide 12, which also constitutes a portion of the subject matter of the aforesaid application. The bail 10 is pivoted at its ends 13 to the sides of the bucket below the center thereof, and the upper portion of the bucket, above the pivoted ends of the bail, is heavier than the lower portion, so that the bucket is mounted in unstable equilibrium 100 and when released, will turn on the pivots of the bail and automatically dump its contents. The bail, which is preferably provided with straight sides, is engaged by resilient catches 14, consisting of strips of metal arranged horizontally and secured at their terminals at 15 to the outer faces of the sides of the bucket, and provided at opposite sides of its center with approximately 105 V-shaped bends 15^a, forming a central ap-

proximately V-shaped notch 16 and angularly disposed outer portions 17. The approximately V-shaped bends of the catches enable the bail to be readily sprung into and out of the central recesses or notches of the side catches, which normally maintain the bucket in an upright position while it is being carried to and from a chute 18. The bucket is also provided at opposite sides 19 with forwardly projecting arms 19, extending upwardly and forwardly at an inclination and equipped with terminal eyes 20 projecting laterally from the arms and receiving flexible guides 21, consisting of ropes or cables arranged on overhead pulleys 22 which are suitably mounted at the upper portion of the portable frame 1. The arms 19, which may be rigidly secured to the outer faces of the sides of the bucket in any preferred manner, are angularly bent at an intermediate point at 19^a to offset their outer projecting portions from the plane of the side walls of the bucket. Each flexible guide rope is composed of two sides 23 and 24 having weights 25 and 26 secured to their lower terminals. The sides or portions 23 of the guiding ropes extend through the eyes 20 of the bucket and also through guiding eyes 27, located at opposite sides of the chute. The weights 25, which are secured to the sides 23, are relatively heavy and are adapted to rest upon the silage or other material to be handled, while the weights 26, which are relatively light, maintain the guiding ropes at the proper tension. The weighted guiding ropes automatically adjust themselves by a descent with the decreasing mass of silage.

The chute 18, which is arranged in an inclined position at the front of the portable frame, is rigidly secured to the same by attaching blocks or pieces 26^a or other suitable means, and the eyes 27 are carried by the arms 28, secured to the sides of the chute and extending rearwardly into the path of the eyes 20 and constituting stops for the same. When the bucket is elevated by the hoisting mechanism, the eyes 20 come in contact with the fixed eyes 27, and stop the upward movement of the front portion of the bucket. The continued upward movement of the rear portion of the bucket causes the same to tilt on the pivots of the bail and the sides of the latter are carried out of engagement with the central notches of the side catches, thereby freeing the bucket, which, owing to its unstable mounting, is adapted to readily tilt and automatically discharge its contents into the inclined chute. After the bucket has discharged its contents, it is lowered and the rearward swinging of the bucket reengages the side catches with the sides of the bail so that the bucket is maintained in an upright position while it is being lowered to the silage and until the

eyes 20 are again engaged with the eyes 27 through the upward movement of the hoisting rope. The upper edge of the front side of the bucket will come in contact with the inner end of the chute 18 when the bucket 70 is lowered, causing the bucket to swing rearwardly so that the bail 10 will be engaged by the catches 14.

In order to avoid twisting the guiding ropes when the bucket is dumped, the eyes 75 20 are provided with horizontal pivots 29, mounted in bearing openings 30 in the projecting portions of the arms 19, and provided with depending approximately L-shaped arms 31 extending downwardly at 80 the inner sides of the fixed arms 19 and projecting outwardly beneath the same and adapted to limit the movement of the eyes in one direction, without affecting the free swinging movement of the arms 19 on the 85 pivots 29 in the dumping of the bucket and the returning of the same to an upright position after dumping. The depending L-shaped arm tends to maintain the pivoted or swiveled guiding eye normally in a horizontal position when the bucket is being raised and lowered. The spaced vertically disposed longitudinally adjustable or extensible guiding ropes are adapted to prevent any horizontal swinging of the bucket and 90 consequent twisting of the hoisting rope, and guide the eyes of the bucket into engagement with the relatively fixed eyes at 95 opposite sides of the chute, whereby the bucket will be positively and automatically 100 dumped at the limit of its upward travel.

While a portable frame, designed particularly for use in connection with silo pits, is illustrated in the accompanying drawings, the improved hoisting mechanism may be permanently mounted, as it is adapted for use wherever it is desired to elevate a bucket and automatically dump its contents into a chute or other receptacle.

What is claimed is:—

1. A hoisting apparatus of the class described including a bucket provided with a pivoted bail, hoisting mechanism connected with the bail for raising and lowering the bucket, a catch mounted on the bucket and engaging the bail for maintaining the bucket normally in an upright position, and means located in the path of the bucket and adapted to swing the same and carry the catch out of engagement with the bail, whereby 115 the bucket is dumped automatically.

2. A hoisting apparatus of the class described including a bucket having a bail and pivotally connected with the same in unstable equilibrium, fastening means mounted on the bucket for engaging the bail to normally maintain the bucket in an upright position, a hoisting device connected with the bail for raising and lowering the bucket, and means arranged in the path of the bucket for 125 130

swinging the fastening means out of engagement with the bail to tilt the bucket and dump its contents.

3. A hoisting apparatus of the class described including a bucket provided with a pivoted bail, a hoisting device connected with the bail for raising and lowering the bucket, a catch mounted on the bucket and provided with a notch receiving the bail for normally maintaining the bucket in an upright position, said catch having angularly disposed portions arranged to permit the bail to be sprung into and out of engagement with the catch, and means located in the path of the bucket and arranged to swing the same out of engagement with the catch.

4. A hoisting apparatus of the class described including a bucket having a pivoted bail, a hoisting device connected with the bail for raising and lowering the bucket, a guide, means carried by the bucket and slideable along the guide, and relatively fixed means also receiving the guide and arranged in the path of the means carried by the bucket and adapted to tilt the latter for automatically dumping the contents thereof.

5. A hoisting apparatus of the class described including a bucket having a pivoted bail, a hoisting device connected with the bail for raising and lowering the bucket, a longitudinally adjustable or extensible guide, an eye carried by the bucket and slideable along the guide, and a relatively fixed eye also receiving the guide and arranged in the path of the eye of the bucket and adapted to tilt the latter.

6. A hoisting apparatus of the class described including a bucket having a pivoted bail, a hoisting device connected with the bail for raising and lowering the bucket, an overhead pulley, a guiding rope arranged on the pulley and having side portions depending therefrom and provided with weights, one of the weights being heavier than the other and adapted to rest upon the material to be handled and to descend as the mass of material decreases in size; an eye carried by the bucket and slideable along the guiding rope, and a relatively fixed eye also receiving the guiding rope and arranged in the path of the eye of the bucket.

7. A hoisting apparatus of the class described including a bucket having a pivoted bail, a catch mounted on the bucket and engaging the bail for normally maintaining the bucket in an upright position, a longi-

tudinal extensible vertically disposed guide, an eye carried by the bucket and slideable along the guide, and a relatively fixed eye 60 also receiving the guide and arranged in the path of the eye of the bucket to tilt the latter and discharge the contents thereof.

8. A hoisting apparatus of the class described including a pivotally mounted 65 bucket, a vertical guide, a pivoted eye carried by the bucket and slideable along the guide, and means arranged in the path of the pivoted eye and receiving the guide for engaging the pivoted eye to tilt the bucket 70 as it is being elevated.

9. A hoisting apparatus of the class described including a pivotally mounted bucket, an arm projecting from the bucket, an eye having a pivot mounted on the projecting arm and provided with a depending approximately L-shaped arm extending beneath the said projecting arm for limiting the movement of the eye, a vertical guide extending through the eye of the bucket, and 80 a relatively fixed eye receiving the guide and arranged in the path of the eye of the bucket for tilting the latter to discharge the contents of the same.

10. A hoisting apparatus of the class described including a fixed chute provided at opposite sides with eyes, a bucket having a pivoted bail, a hoisting device connected with the bail for raising and lowering the bucket, arms projecting from the bucket and 90 provided with eyes, extensible flexible guides located at opposite sides of the chute and extending through the eyes thereof and slideably receiving the eyes of the bucket, the latter being adapted to engage the eyes of 95 the chute to cause a tilting movement of the bucket, and yieldable means carried by the bucket for engaging the bail to maintain the bucket normally in an upright position.

11. A hoisting apparatus, comprising a 100 pivotally mounted bucket, means for elevating the bucket, a vertical guide, arms connected to the bucket, means connecting the arms to the guide and forming a pivot for the arms, during the dumping of the bucket, 105 and means located in the path of said means for engaging the same for tilting the bucket.

In testimony, that I claim the foregoing as my own, I have hereto affixed my signature in the presence of two witnesses.

HENRY SANTROCK.
